UNITED STATES PATENT OFFICE

WILLIAM P. CRAIG, OF SHELBY, NORTH CAROLINA, ASSIGNOR OF ONE-HALF TO CLEVELAND CLOTH MILL COMPANY, OF SHELBY, NORTH CAROLINA, A CORPORATION OF NORTH CAROLINA

TIMING DEVICE FOR LOOM STOP MECHANISM

Application filed March 29, 1932. Serial No. 601,861.

This invention relates to an attachment for looms; and more particularly, for what may be termed a selective stop motion attachment for use on looms equipped with a stop motion, by which term is included means for applying and disconnecting power from the loom and braking mechanism and a filling detector adapted to be operated by the exhaustion of the thread on the shuttle. The detector may operate either mechanically or electrically.

It is the present practice to arrange a lever operatively connected to the loom power control and braking device in such manner that it can be rocked into the path of the lay by a suitable mechanical device operated by the filling detector, so that upon the thread becoming exhausted, the filling detector will operate to rock the knock-off lever into the path of the lay whereupon the lay will strike the knock-off lever and operate same to disconnect the drive power from the loom and brake the loom. Such direct action by the lay on the knock-off lever is, however, objectionable as it stops the loom on the first pick, as the filling detector or filler makes contact with the quill in the shuttle with the shuttle being in the left hand box of the loom. Where the loom is operated as on a crepe weave, with a two and two box motion, it would be necessary for the weaver to start the loom and let it run for three picks, and then stop the loom by hand to stop the loom with the shuttle in the right hand box where it could be conveniently removed and replaced.

The present invention relates to an attachment intended to be interposed between the feeler actuated mechanism and the knock-off lever in such a way that the lay will be permitted to travel a predetermined number of picks, as for instance, two, four, or eight, after the operation of the filling detector or feeler before the knock-off lever will be rocked into position to be engaged by the lay.

The invention consists in the novel construction, arrangement and combination of parts hereinafter more particularly described and claimed.

50 Two sheets of drawings accompany this

specification as part thereof, in which like reference characters indicate like parts throughout.

In the drawings:—

Figure 1 is a fragmentary perspective of a 55 part of a loom showing parts of the knock-off lever, the lay, and the filler actuated mechanism with the present invention in position;

Figure 2 is a back elevation view of the improved attachment; 60

Figure 3 is a front elevation of the device;

Figure 4 is a vertical medial cross section through the device; and

Figure 5 is a vertical transverse cross section 65 through the device.

Referring to the drawings:—

Numerical 1 indicates a solenoid device having electrical connections 2 with a feeler or filling detector (not shown) by means of 70 which exhaustion of the thread in the shuttle will cause an electrical current through conductors 2 to actuate solenoid 1 to rock lever 3 and link 4.

The lay of the loom is provided with a 75 bumper bolt 5 adapted to strike the head 6 of a knock-off lever 7 connected to power and braking controls (not shown), when the lever 7 is rocked into such a position that bolt 5 on the lay engages the head 6. It is the present practice to connect head 6 directly with solenoid 1 by means of a link corresponding to link 4. The present invention, however, contemplates interposing a timing stop mechanism between link 4 and head 6 by means 80 of which the lever 7 will be selectively rocked a predetermined number of picks after the energizing of solenoid 1 by the feeler.

The timing attachment consists of two 90 parallel spaced frame plates 11 and 12, which are secured in spaced parallel relation to each other by means of collars 13 and bolts 14, and which are secured to the loom frame by means of bolts passing through holes 15 provided on plate 12.

A slide 17 is positioned in suitable grooves provided on the inner faces of plates 11 and 12 so as to be vertically slidable through said plates, and this slide 17 is provided near its lower end with a slot 18 through which 100

extends an operating lever 10. The upper end of slide 17 is connected, as through a hole 19, with the link 4 and through this link with the solenoid.

5 The operating lever 10 is pivoted at its rear end, as at 20, between two links 21, these links being pivoted in turn between the frame plates, as by bolt 22. A ratchet operating arm 23 is also pivoted to links 21, as at 23', 10 and arm 23 operatively engages a ratchet wheel 24 mounted between the plates on spindle 25, which extends through and beyond the plates on each side. The arm 23 is further provided with an offset shoulder 28, 15 which is connected as by spring 29 with one of the spacing bolts 14 in such manner as to hold arm 23 in constant operative relation to ratchet wheel 24.

A pawl 30 is pivoted between the plates, 20 as at 31, being controlled by spring 32 secured to a pin 33 fixed in one plate. On one end of spindle 25 is mounted a cam member 26 having a plurality of convex cam faces 34, here illustrated as two diametrically opposed 25 parts. A cam lever 35 is pivotally mounted to the adjacent frame plate 11, as at 37, and is held as by spring 35' with its cam engaging part 36 in constant engagement with the cam member 26. This cam lever 35 is further 30 provided at its front end with a depending part 38 which terminates in a hook or finger 39 which extends under operating lever 10.

On the opposite side of the device and the other end of spindle 25 is mounted a second 35 cam member 27 provided with a plurality of concave cam faces 30, here illustrated as two oppositely disposed depressions. A cam lever 9 having a cam engaging projection 41 is pivotally mounted on plate 12, as at 43, 40 and is held, as by spring 9', in constant engagement with cam member 27. The free end of cam lever 9 is provided with a hole 44 to which may be connected link 8 which in turn is connected to head 6 of knock-off lever 7 45 when in assembled position on the loom.

When in position on the loom, the attachment is arranged as illustrated in Figure 1, from which it will be noted that operating lever 10 extends adjacent knock-off lever head 6, and is directed toward the bumper bolt 5 of the lay, and as thus assembled it will be noted that link 4, instead of being connected directly to the knock-off lever 7 through its head 6, is instead connected to the 55 slide member 17 of the attachment, and the head 6 of the knock-off lever 7, instead of being connected directly to the solenoid, is connected by link 8 to the cam lever 9 of the attachment.

60 With the attachment in position on the loom, as illustrated in Figure 1, both the knock-off lever head 6 and the operating lever 10 are below the path of the bumper bolt 5 of the lay, and in what may be termed inoperative position. Assuming that the filling

detector operates by reason of the exhaustion of thread in the shuttle, solenoid 1 will be energized by electric current passing through conductors 2, and lever 3 rocked, thus elevating slide 17 and raising operating lever 10 70 into the path of bolt 5 of the lay. When the bolt engages operating lever 10, it will be forced rearwardly rocking links 21 until ratchet arm 23 rises behind a tooth of ratchet wheel 24. The lay having continued its reversed movement and released operating lever 10, permits spring 29 to retract, thus drawing rearwardly operating lever 10 and ratchet wheel 24 to the extent of one tooth, 75 in which position ratchet wheel 24 will be held by pawl 30. This partial revolution of ratchet wheel 24 and spindle 25 will have caused the convex face on cam member 26 to have moved out of engagement with the cam 80 engaging part of lever 35, and spring 35' will accordingly raise lever 35 and cause hook or finger 39 to engage operating lever 10, and thus hold this operating lever up in the path of bolt 5 of the lay. Successive picks will repeat the movements of operating lever 10 until the cam 27 on the rear of spindle 25 is sufficiently rotated to permit cam engaging part 41 of lever 9 to enter one of the concave cam faces 40 being drawn upwardly and into such engagement by means of spring 9'. 85

The lever 9 being connected by link 8 to knock-off lever 6 will thus elevate knock-off lever head 6 also into the path of bumper bolt 5 of the lay, and thereupon on the next stroke of the lay, knock-off lever 7 will be 90 operated, and at the same time operating lever 10 will also be operated, rotating spindle 25 one more fractional turn which will be sufficient to lower levers 35 and 8 as well as the knock-off lever head 6, leaving the entire device in its initial position as illustrated in Figure 1, and ready for a repetition of the same operating cycle. 95

It will be apparent that by modifying the 100 number of cam faces on cams 26 and 27, and the number of teeth on ratchet wheel 24, the number of picks intervening between the initial operation of the filler device and the ultimate operation of the knock-off lever may be modified as may be desired, and thus a substantial range in adjustment is permitted and considerable flexibility in the operation of the loom. 110

Various modifications will readily suggest 115 themselves in the form and construction of parts, but all within the scope of the present invention as claimed. 120

What I claim is:

1. A control device for looms having a 125 knock-off lever movable into and out of the path of the lay and a shuttle feeler operable by the exhaustion of weft from the shuttle; comprising an operating member movable into and out of the path of the lay, means operatively connecting said member with the 130

shuttle feeler device in such manner that said member is moved into the path of the lay upon exhaustion of the weft, and selective means connecting the knock-off lever and said operating member whereby the striking of said last mentioned member by the lay will operate after a predetermined number of picks to throw the knock-off lever into the path of the lay.

2. The device of claim 1 in which the selective means includes two levers, one of said levers having means adapted to engage the said operating member and the other connected to the knock-off lever and means operated by engagement of the lay with said operating member to operate the first mentioned lever whereby it will hold the operating member for a predetermined number of picks, in the path of the lay.

3. The device of claim 1 in which the selective means includes two levers, one having means engaging the operating lever and the other connected to the knock-off lever, a ratchet wheel adapted to be operated by reciprocation of the operating lever by the lay, and cam members rotatable with and by the ratchet operative of the said levers.

4. The device of claim 1 in which the selective means includes two levers, one having means engaging the operating lever and the other connected to the knock-off lever, a ratchet wheel adapted to be operated by reciprocation of the operating lever by the lay, and cam members rotatable with and by the ratchet operative of the said levers, said cam members each having a plurality of circumferentially spaced cam faces whereby a predetermined sequence is obtained in the operation of the operative lever and the two other levers specified.

5. In combination with a loom, of that type having a knock-off lever controlling the power and braking means of the loom and a feeler operative by the exhaustion of thread from the shuttle, means operated by the feeler for selectively rocking the knock-off lever into the path of the loom lay a predetermined number of picks after the feeler is actuated, comprising an operative lever rockable into and out of the path of the lay, means connecting the feeler with the operative lever adapted to rock the latter into the path of the lay, means operated by the operative lever while in the path of the lay and actuated by the successive engagements of the lay with said operative member to hold the operative member in said path during a predetermined number of strokes of the lay, and means actuated by the operative member and connected with the knock-off lever to rock said knock-off lever into the path of the lay after a predetermined number of strokes of the lay, and means whereby the concurrent striking of the knock-off lever and operating lever will

cause both of said levers to rock out of the path of the lay.

6. An attachment for looms comprising a frame adapted to be secured to the frame of the loom and including spaced bearing plates, a spindle journaled in said plates, a ratchet fixed on the spindle intermediate the plates, a pawl controlling the ratchet, a spring controlled lever between the plates having an arm operative of the ratchet, a cam fixedly mounted on each end of the spindle, a lever mounted on the outer face of each plate having a cam engaging part, the lever on one side having a terminal hook adapted to engage the ratchet operating lever and the cam on that side having circumferentially spaced convex cam faces adapted to periodically raise the lever in engagement therewith, the cam on the other side having circumferentially spaced concave cam faces adapted to periodically lower the lever in engagement therewith.

7. An attachment for looms comprising a frame adapted to be secured to the frame of the loom and including spaced bearing plates, a spindle journaled in said plates, a ratchet fixed on the spindle intermediate the plates, a pawl controlling the ratchet, a spring controlled lever between the plates having an arm operative of the ratchet, a cam fixedly mounted on each end of the spindle, a lever mounted on the outer face of each plate having a cam engaging part, the lever on one side having a terminal hook adapted to engage the ratchet operating lever and the cam on that side having circumferentially spaced convex cam faces adapted to periodically raise the lever in engagement therewith, the cam on the other side having circumferentially spaced concave cam faces adapted to periodically lower the lever in engagement therewith, a slide member having means for engaging the ratchet operating lever and guide means on the plates for said slide member.

In testimony whereof, I affix my signature. 110
